UNITED STATES PATENT OFFICE.

WILLIAM E. PATNAUDE, OF HAVERHILL, MASSACHUSETTS, ASSIGNOR OF ONE-HALF
TO WILLIAM C. COLESTON, OF HAVERHILL, MASSACHUSETTS.

WATER-COOLER FAUCET.

1,078,213.

Specification of Letters Patent.

Patented Nov. 11, 1913.

Application filed January 27, 1912. Serial No. 673,747.

To all whom it may concern:

Be it known that I, WILLIAM E. PATNAUDE, a citizen of the United States, residing at Haverhill, in the county of Essex and State of Massachusetts, have invented an Improvement in Water-Cooler Faucets, of which the following is a specification.

This invention relates to certain improvements in faucets which are designed for use 10 in connection with water-coolers, or where it is desired to open the faucet by pushing the operating means inwardly.

The object of my invention is to produce a faucet of the above type which may be 15 easily opened, and which is of simple and durable construction. I accomplish this object by the means shown in the accompanying drawing, in which,

Figure 1 is a central longitudinal sectional view of a faucet made according to 20 my invention. Fig. 2 is a similar view showing the parts in open position. Figs. 3 and 4 are respectively cross sectional views on the lines 3—3 and 4—4 of Fig. 1.

25 In the drawing *a* indicates a tubular outer casing open at its outer end and having an inlet port at its inner end into which the inlet pipe *b* is threaded. A tubular stem *c* having a passage throughout its end length, is threaded into an annular rib *a'* within the casing *a*, so that said stem is in open communication with the inlet port thereof. The outer end of said stem is provided with an outwardly flaring conical 30 shaped valve *c'*, although the form thereof is not material. An inner casing *d* is slidably mounted within the outer casing *a*, and is provided with an inwardly projecting flange or rib *d'*, having a packing washer *e* 35 therein which engages the outer surface of the stem *c*, so as to make a water-tight connection therewith, yet permitting said casing to slide freely thereon. A cap *f* is threaded into the outer end of the inner casing *b*, to close the end thereof, and a valve-seat washer *g* is clamped between said cap and a rib *h* on the inner casing *d*. The inner casing *d* is provided with a discharge nozzle *i* which leads from the under side thereof 40 midway between the valve-seat *g* and the packing *e*, through a slot *a²* in the outer casing, and in which the nozzle may be moved longitudinally of the casing. A spring *j* is arranged between the rib *a'* on 45 the outer casing and the rib *d'* on the inner

casing, and acts to hold the seat *g* against the valve *c'*. Under normal conditions the water will flow through the stem *c* into the chamber formed within the cap *f*, and, if there is any effective water pressure, such 60 pressure will be applied to the inner side of the cap *f*, and will assist the spring *j* in holding the valve seat *g* against the valve *c'*. In this position, the cap *f* will project some distance beyond the end of the outer casing *a*. 65

To open the valve, the inner casing *d* is pressed inwardly by pressing against the cap *f*, so that it is moved into the position shown in Fig. 2, permitting the water to 70 pass from the chamber within the cap about the valve over the valve-seat and through the discharge nozzle. When released, the valve will close automatically. The casing *d* is guided both within the outer casing *a* 75 and upon the surface of the valve stem *c*, so that possibility of binding is avoided.

I claim:—

1. A faucet comprising a tubular outer casing having an inlet port at one end and 80 open at the opposite end, an open-ended tubular stem rigidly mounted at one end within said casing and opening to said port, said stem having an exteriorly disposed annular valve on its opposite end, a tubular 85 inner casing slidably mounted in the open end of said outer casing and having its outer end closed to provide a chamber, and its inner end open and slidably mounted on said stem, a side discharge port, and a valve 90 seat between said discharge port and said chamber disposed to engage said valve, substantially as described.

2. A faucet comprising a tubular outer casing having an inlet port at one end and 95 open at the opposite end, an open ended tubular stem rigidly mounted at one end within said casing and opening to said port, said stem having an exteriorly disposed annular valve on its opposite end, a tubular 100 inner casing extending into said outer casing from its outer end and having its inner end open and slidably mounted on said stem, and its outer end closed and providing a chamber, a side discharge port, and a 105 valve-seat between said discharge port and said chamber disposed to engage said valve, substantially as described.

3. A faucet comprising a tubular outer casing having an inlet port at one end and 110

- open at the opposite end, an open ended tubular stem rigidly mounted at one end within said casing and opening to said port, said stem having an exteriorly disposed annular valve on its opposite end, a tubular inner casing slidably fitted in the open end of said outer casing and having its outer end closed to provide a chamber and its inner end open and fitted to slide on said stem, 5 a side discharge port and a valve-seat between said discharge port and said chamber disposed to engage said valve and limit 10

the outward movement of said inner casing at a point at which its outer end projects some distance beyond the end of said outer casing; substantially as described. 15

In testimony whereof, I have signed my name to this specification, in the presence of two subscribing witnesses.

WILLIAM E. PATNAUDE.
